UNITED STATES PATENT OFFICE.

ALLEN A. HORTON, OF PLYMOUTH, MICHIGAN, ASSIGNOR, BY MESNE ASSIGNMENTS, TO THE EATON AXLE & SPRING COMPANY, OF CLEVELAND, OHIO, A CORPORATION OF OHIO.

CLOSURE.

Application filed October 6, 1926. Serial No. 139,896.

This invention relates to improvements in closures of the type provided with opposed locking fingers for co-operation with the opposed cam portions of the device to be closed.

5 The object of the present invention is the provision of an improved closure of the character described which comprises separated inner and outer walls each of one piece of metal and effectively associated together so as to prevent movement therebetween, with a locking member having its body portion arranged between said walls.

10 Further objects of the invention are in part obvious and in part will appear more in detail hereinafter.

In the drawings, Fig. 1 is a vertical sectional view of my improved closure applied to a tubular filler member; Fig. 2 is a bottom plan view of the closure; Fig. 3 is a vertical sectional view thereof, taken on the line 3—3, Fig. 2; Fig. 4 is a plan view of the tubular member of Fig. 1; and Fig. 5 is a vertical sectional view of said tubular member, taken on the line 5—5, Fig. 4.

25 The closure illustrated in the drawings includes an outer wall and an inner wall, separated to provide an air chamber 1 therebetween. Said outer wall includes a top portion 2 provided with a centrally disposed, circular dome 3 and a depending, marginal skirt portion 4 provided with longitudinal corrugations, said top and skirt portions preferably being of integral form, as shown.

The inner wall includes a centrally disposed cup-shaped portion having a cylindrical body 5 and a circular bottom 6; a horizontal annular flange portion 7 extending outwardly from the upper end of the body 5 and engaging the top portion 2 of the outer wall 40 surrounding the central dome thereof; and an annular flange or skirt portion 8 depending from the outer edge of said horizontal flange portion 7 and longitudinally corrugated to correspond to the corrugated skirt portion 4 of the outer wall. The inner depending flange portion 8 is of such size in cross dimension as to snugly or closely engage the outer skirt portion 4 and is of substantially the same length or depth as said outer skirt portion, as clearly indicated in the drawings. Preferably, and as shown, the three portions 50 of the inner wall, to-wit, the cup-shaped portion, the horizontal flange portion and the

depending flange portion, are all of integral form.

55 The outer and inner walls are maintained in assembled relation by bending the bottom edge portion of the depending skirt 4 of the outer wall inwardly around the bottom edge portion of the depending flange 8 of the inner wall, as indicated at 10 in the drawings. Relative rotary movement of the two walls is prevented by the interlocking corrugated skirt or flange portions 4, 8 thereof.

60 When the closure is applied to the device to be closed, the air chamber 1 thereof is vented to the atmosphere by the aperture 12, in the dome 3 of the outer wall, and is vented to the inside of the device to be closed through two opposed openings 13 in the cup-shaped portion of the inner wall. Said openings 13 are at substantially the junction of the cylindrical body 5 and the circular bottom 6 of said cup-shaped portion and are adapted to have extended therethrough the spring end portions 15 of a locking member 16 arranged within said cup-shaped portion. Said locking member comprises a strip of spring metal and has its middle portion riveted or otherwise suitably secured, as at 17, to substantially the center of the bottom 6 of the cup-shaped portion. The ends of said locking member project outwardly beyond the cylindrical body 5 of said cup-shaped portion and are adapted to yieldingly engage the opposed 75 cam portions of the device to be closed, as will later appear.

70 In the present embodiment of the invention, the device to be closed is an automobile fuel tank 20 having the cam portions for co-operation with the spring fingers 15 of the closure carried by an upwardly extending filler neck. Said neck includes a cylindrical body portion 21 which may be an integral part of the tank 20 or separate therefrom and provided with a base flange 22 for attachment thereto around the edge of the opening 23 in said tank. At its upper end, said body portion 21 is provided with an inwardly extending, substantially horizontal flange 24 terminating in a depending flange 25. At two diametrically opposite points, portions of flanges 24 and 25 are cut away so as to provide two passageways 26, through which the locking fingers 15 of the closure are adapted to be 80 passed, as will later appear. The cutting

away of said flanges provides two depending flanges 25 of substantially semi-circular form, and the bottom edges of these flanges are inclined to provide cam portions 27 with 5 which the locking fingers 15 of the closure are adapted to co-operate in effecting detachable locking connection of the closure with the neck portion 21 of the tank. At the rear ends of the cam portions 27 are provided recessed dwell portions 28, in which the locking fingers of the closure are adapted to engage when the closure is in fully seated position on the neck portion. Just beyond said dwell portions, the depending flanges 25 are provided 10 with depending lugs or projections 29 which provide stops for the locking fingers of the closure when said fingers are travelling up the cam portions 27.

The closure is applied to the neck portion 20 21 in the usual manner of bayonet joint connections, the locking spring fingers 15 of the closure being passed down through the passageways 26 of said neck portion. The closure is then turned in a clockwise direction, 25 which causes the locking fingers thereof to ride up the cam portions 27 with yielding effect, the rotary movement of the closure being continued until said fingers strike the stop portions 29 which denotes full seating position 30 of the closure. To remove the closure, it is only necessary to turn it in the reverse direction, whereupon the spring fingers thereof will leave the dwell portions 28 and ride down the cam portions. The closure 35 can then be removed from the neck portion, the locking fingers of the closure being passed through the passageways 26, as before.

Preferably, the closure is provided with a yielding gasket 32 which is adapted to lie 40 between the horizontal flange 24 of the neck portion and the top portion 2 of the closure outer wall when the closure is applied to the neck portion. It is of substantially the same width as the annular chamber formed 45 by the depending flange portion 8 and the cup-shaped portion 5, 6 of the inner wall, and is maintained within said chamber, even when the closure is removed from the neck portion 21, by the projecting outer ends of 50 the spring fingers 15.

When the closure is applied to the neck portion 21 of the tank, as indicated in Fig. 1, the spring fingers 15 of the closure are

near the bottom of the openings 13 in the cup-shaped portion of the inner wall, so 55 that said openings are effectively baffled against the normal escape therethrough of the liquid fuel in the tank 20.

What I claim is:

A closure for devices having opposed cam portions, comprising a one piece outer wall and a one piece inner wall, said inner wall including a depending cup-shaped portion, an outwardly extending annular portion at the top thereof, and a depending cylindrical axially corrugated skirt portion at the outer edge of said annular portion, said outer wall including a central portion and a depending cylindrical axially corrugated skirt portion at the outer edge thereof, said central portion of the outer wall overlying the cup-shaped and annular portions of the inner wall and contacting with the latter portion, whereby an air chamber is provided between the cup-shaped portion of the inner wall and the central portion of the outer wall, said central portion being provided with an aperture 70 venting said chamber to the atmosphere, the skirt portions of the inner and outer walls being arranged in interlocking relation with the lower end of the skirt portion of the outer wall bent inwardly beneath the skirt portion of the inner wall so as to firmly maintain the two walls in assembled relation, the interlocking corrugations of the skirt portions of 75 the two walls preventing relative rotary movement thereof, the cup-shaped portion of the inner wall being provided in its side with two opposed openings which vent the air chamber to the inside of the device to be 80 closed when the closure is applied to said device, and an elongated inherently resilient locking member arranged in said air chamber, said locking member intermediate its ends being secured to the bottom part of the 85 cup-shaped portion of the inner wall and having its two end portions projecting outwardly through the opposed openings of said cup-shaped portion, whereby said projecting end portions of the locking member are free 90 for engagement with the cam portions of the device to be closed when the closure is applied thereto.

In testimony whereof I hereby affix my signature.

ALLEN A. HORTON.
